UNITED STATES PATENT OFFICE

FRED L. V. SPRING, OF WATERBURY, CONNECTICUT, ASSIGNOR TO THE CHASE COMPANIES, INCORPORATED, OF WATERBURY, CONNECTICUT, A CORPORATION

PUMP-TYPE OILER

Application filed January 31, 1931. Serial No. 512,580.

This invention relates to improvement in oilers and particularly to oilers of the type which are provided with pump-mechanisms for forcibly ejecting oil therefrom.

5 The main object of my present invention is to provide at a low cost for manufacture a convenient and effective pump-type oiler constructed with particular reference to simplicity and reliability.

10 With the above and other objects in view as will appear from the following, my invention consists in a pump-type oiler having certain details of construction and combinations of parts as will be hereinafter described and particularly recited in the claims.

In the accompanying drawings:

Fig. 1 is a view in side elevation of a pump-type oiler embodying my invention;

Fig. 2 is a view thereof in vertical central 20 section but on a larger scale;

Fig. 3 is an underside view thereof, with the bottom-plate omitted;

Fig. 4 is a detail sectional view taken on the line 4—4 of Fig. 2;

25 Fig. 5 is a view in side elevation of the unit comprising the spherically-contoured piston, together with its operating-stem, detached; and

30 Fig. 6 is a perspective view of the pump-cylinder detached.

In the embodiment of my invention herein chosen for illustration, I employ an oil-reservoir consisting of a substantially-cylindrical sheet-metal body-member 10 provided at its 35 upper end with a threaded neck 11 for the reception of a filler-cap 12 and having crimped to its lower edge a bottom-plate 13.

Projecting upward from the sloping shoulder-portion 14 of the body-member 10 is a 40 tubular spout 15 soldered at 16 to the said shoulder-portion, and having its inner end 17 projecting within the interior of the body-member 10.

45 Secured to the inner end 17 of the spout

15 by means of solder 18 is a valve-housing 19 having an axial recess 20 into which the lower end 17 of the said spout projects and in which is located a plate-like check-valve 21 adapted to close a passage 22 in the said valve-housing to prevent reverse flow of oil therethrough, as will hereinafter appear. The said valve 21 plays back and forth between the extreme lower edge of the inner end 17 of the spout and the bottom-wall of the 50 recess 20.

Soldered or otherwise secured to the periphery of the valve-housing 19 is a pump-cylinder 23 depending therefrom and provided in its lower portion with four (more or less) slot-like ports 24 which preferably 55 intersect its lower edge.

Housed within the cylinder 10 is a compression-spring 25 bearing at its upper end against the underface of the valve-housing 19 and at its lower end bearing against a piston 26 which, as shown, is preferably 60 spherically contoured to permit it to tilt within the said cylinder without occasioning a bind. Projecting radially from the underface of the piston 26 is a piston-stem 27 preferably soldered in place and having its outer end bent over to form a hook 28.

65 The hooked end 28 of the piston-stem 27 is passed through a perforation 29 formed in one end of a substantially-horizontal rocking-lever 30 which is pivoted between its ends upon a stud 31 laterally offsetting from a bracket-plate 32 in turn radially projecting toward the center of the body-member 10 70 from the wall thereof, to which it is secured by means of solder, as at 33.

75 The bracket-plate 32 adjacent its lower inner corner is bent laterally to provide a stop-finger 34 engaging with the under-edge 85 of the lever 30 to limit the swinging movement thereof under the urge of the spring 25.

The end of the lever 30 opposite the stem 28 is pivotally connected by means of a stud 35 to the lower arm 36 of a substantially L- 90

shaped operating-plunger 37, the upper arm 38 of which projects outward through a perforation 39 in the shoulder-portion 14 of the body-member 10 and is provided at its extreme outer end with a finger-button 40. The upper arm 38 of the operating-plunger 37 slides back and forth through and rocks in a fibrous washer 41 clamped in place against the outer face of the shoulder-portion 14 by 10 means of an escutcheon 42.

When the piston 26 is at the lower limit of its movement, the upper ends of the slot-like ports 24 will be uncovered to permit oil to flow by gravity into the interior of the cylinder 23 above the said piston. Now, when the plunger 37 is depressed by means of its finger-button 40, its arm 38 will slide through the opening 39 and the washer 41 and, at the same time, rock therein, to depress the end 20 of the lever 30 to which it is pivotally connected and correspondingly raise the opposite end which plays up and down in one of the ports 24, so as to move the piston 26 upward. This upward movement of the piston first 25 closes the connection between the ports 24 and that portion of the interior of the cylinder 23 lying above the piston, and thereafter positively forces the oil upward through the passage 22, past the check-valve 21 and thence 30 upward and out through the spout 15.

When pressure is relaxed from the finger-button 40, the piston will be depressed by the spring 25 and the parts will be restored to the positions in which they are shown in Fig. 2, 35 in which the check-valve 21 will be in position to prevent the reverse flow of oil previously forced upward into the spout 15.

Owing to the spherically-contoured character of the periphery of the piston 26, the 40 same will rock within the cylinder 23 to compensate for the sweep of the lever 30 so that the necessity for a link is obviated. Furthermore, by mounting the plunger 37 so that its upper arm both slides and rocks in the 45 body-member 10, or a bearing secured thereto, the necessity for elaborate linkage is avoided.

Attention is also called to the fact that by providing the cylinder 23 with one or more 50 ports 24 which are automatically covered and uncovered by the piston itself, the necessity for a suction-valve is avoided, since the oil will flow into the cylinder through the said ports by gravity. When the oil level 55 comes low, practically the last remaining part thereof may be ejected by tipping the can into a horizontal position with its spout and pump-mechanism lowermost.

It will be understood by those skilled in 60 the art that my invention may assume varied physical forms without departing from my inventive concept, and I, therefore, do not limit myself to the specific embodiment herein chosen for illustration, but only as indicated in the appended claims.

I claim:

1. In a pump-type oiler, the combination with the oil-reservoir and spout thereof; of a pump-cylinder formed with one or more laterally-opening longitudinal slot-like ports; a piston reciprocating in the said cylinder and constructed and arranged to alternately open and close communication through said ports between the said reservoir and that portion of the interior of the said cylinder located between the piston and the said spout; and means including a member moving in one of said slot-like ports for manually actuating the said piston. 70 75

2. In a pump-type oiler, the combination with the oil-reservoir and spout thereof; of a pump-cylinder formed with one or more laterally-opening longitudinal slot-like ports; a piston shorter in length than one of said slot-like ports and reciprocating in the said cylinder in position to alternately open and close communication through said ports between the said reservoir and that portion of the interior of the said cylinder located between the piston and the said spout; and means including a member moving in the outer end of one of said slot-like ports for manually operating the said piston. 80 85 90

3. In a pump-type oiler, the combination with the oil reservoir, pump-cylinder and piston thereof; of a manually-operable actuating-member for the said piston; and a lever connecting the said actuating-member to said piston in such manner as to cause the latter to concurrently reciprocate and oscillate in the said cylinder. 95 100

4. In a pump-type oiler, the combination with the oil-reservoir and pump-cylinder thereof; of a spherically-contoured piston movable in the said pump-cylinder; and manually-operable means connected to the said spherically-contoured piston for concurrently reciprocating and oscillating the same in the said cylinder. 105

5. In a pump-type oiler, the combination with the oil-reservoir and spout thereof; of a pump-cylinder located in the said reservoir; a piston in the said cylinder; and actuating-means for the said piston including a lever connected at one end to the said piston, a combined rocking-and-reciprocating plunger pivoted to the opposite end of the said lever and both sliding and rocking in a bearing in the oiler-body from which it outwardly projects. 110 115 120

6. In a pump-type oiler, the combination with the oil-reservoir and spout thereof; of a pump-cylinder located in the said reservoir; a piston in the said cylinder; and actuating-means for the said piston including a lever connected at one end to the said piston, a substantially L-shaped combined rocking-and-reciprocating plunger having one of its arms pivoted to the opposite end of the said lever and its other arm both sliding and rock- 125 130

ing in a bearing in the oiler-body from which it outwardly projects.

7. In a pump-type oiler, the combination with the oil-reservoir and pumping-mechanism for forcibly ejecting oil therefrom; of an actuating-member for the said pumping-mechanism including a member projecting through a bearing-opening in the oiler-body and both reciprocating and rocking therein.

10 In testimony whereof, I have signed this specification.
